(Continued)

Primary Examiner — Melody N Brown(74) *Attorney, Agent, or Firm* — Dorsey & Whitney LLP(57) **CLAIM**

The ornamental design for an automobile and/or replica thereof, as shown and described.

DESCRIPTION

FIG. 1 is a left, rear perspective view of an automobile and/or replica thereof showing our new design;

FIG. 2 is a right side elevation view thereof.

FIG. 3 is a front elevation view thereof.

FIG. 4 is a rear elevation view thereof.

FIG. 5 is a left side elevation view thereof.

FIG. 6 is a top plan view thereof; and,

FIG. 7 is a left, front perspective view thereof.

The portions of the automobile shown in broken lines are for environmental and illustrative purpose and form no part of the claimed design.
